RESIDENTIAL BUILT-IN VACUUM CLEANER

Edward J. Stone, Springfield, Ohio, assignor to Robbins & Myers, Inc., Springfield, Ohio, a corporation of Ohio

Filed Feb. 12, 1965, Ser. No. 83,801

Term of patent 7 years

(Cl. D9—2)

FIG. 1

FIG. 2

FIG. 3

FIG. 4

FIG. 1 is a perspective view of a residential built-in vacuum cleaner, showing my new design.

FIG. 2 is a side elevation of the same.

FIG. 3 is a side elevation of the same as seen from the right side of FIG. 2; and

FIG. 4 is a top plan view of the same.

The dominant features of my design reside in the portions shown in full lines.

The broken line portions of the vacuum cleaner are shown broken away in FIGURE 3, and partially omitted in FIGURES 1 and 2, for convenience of illustration.

I claim:

The ornamental design for a residential built-in vacuum cleaner, as shown and described.
